UNITED STATES PATENT OFFICE.

CLARENCE H. RASMUSSEN, OF DES MOINES, IOWA.

HEATING STOVE.

Application filed March 10, 1924. Serial No. 698,114.

The object of my invention is to provide an auxiliary heater device of simple, durable and inexpensive construction designed to be applied to an ordinary heating stove or furnace for the purpose of materially increasing radiation from the heating stove or furnace.

A further object is to provide a heater device of the character described, so constructed and arranged that a strong circulation of air will be maintained within the interior of the heater device, to thereby discharge additional heated air into the room to be heated, and at the same time increase the radiation from the outer walls of the combustion chamber of the stove or furnace.

My invention consists in the construction, arrangement and combination of the various parts of the device, whereby the objects contemplated are attained, as herein-after more fully set forth, pointed out in my claims, and illustrated in the accompanying drawings, in which:

Figure 1 shows a vertical central sectional view of a heating stove having my improved heater device applied thereto. The arrows in said figure illustrate the direction of the flow of air currents into and out of said heater device.

Figure 2 shows a top or plan view of the heater device detached from the stove.

Referring to the accompanying drawings, I have used the reference numeral 10 to indicate generally the stove or furnace to which my improvement is applied. The top of the stove or furnace is indicated by the numeral 11 and is provided with a central opening at its top which is usually covered with a lid, not shown, so that a kettle or other article to be heated may be placed thereon when the lid is removed. The top 11 is also provided with a flue member 12.

My improved auxiliary heater device comprises a hollow body 13 preferably made of cast metal and open at its top. The bottom and sides of the heater body 13 extend upwardly and outwardly to a point spaced apart from the interior of the combustion chamber sufficiently to provide ample room for a passageway of the products of combustion to the flue. This heater body 13 may be made in various sizes and shapes to suit the conditions of the stoves or furnaces of different sizes and shapes.

In use the products of combustion arising from the fire in the stove or furnace will be

deflected by the heater body outwardly and upwardly and be caused to travel in close contact with the walls of the stove or furnace, thereby increasing the heat applied to said walls and the corresponding radiation of heat from the outer surface of the combustion chamber walls.

The top of the heater body is connected to the under surface of the stove top 11 by means of screws 14, although it may be supported in any ordinary way.

At the center of the opening in the top of the heater body 13 is a screw threaded collar 15 supported by braces 16 which extend outwardly and are connected to the top portion of the heater body. Mounted in the collar 15 is a fresh air supply pipe 17 having its lower end resting upon the bottom of the heater body and formed with large air circulating openings 18 at its lower end.

Mounted on top of the pipe 17 is a head 19 formed hollow and provided with a central opening 20 at its top, and with a number of radially extending hollow arms 21 open at their outer ends and communicating with the interior of the head at their inner ends. These hollow arms are preferably substantially flat on top to form a convenient support for a tea kettle or other vessel to be heated. These arms 21 are above the top of the stove, and extend outwardly beyond the opening in the top of the stove.

Hence, with my improvement, I not only increase the radiation of heat from the outer walls of the combustion chamber due to the heat deflecting action of my heater device, but I also provide an additional source of radiated heat from within the interior of the heater device, which I have demonstrated is almost equal to the radiation from the outer walls of an ordinary heating stove.

As an additional means for delivering relatively cool air to the interior of the heater device and avoiding the retarding action of the currents of heated air arising from the bottom of the heater device, I have provided the pipe 17. When the opening 20 at the top of this pipe is not obstructed, relatively cool air will pass straight down through it to the bottom of the heater device. When, however, a tea kettle or other article is placed on top of the hollow arms 21, the central opening 20 is closed, but relatively cool air is admitted into the outer ends of the hollow arms 21, and the presence of a tea kettle or the like full of relatively cool water on top

2
of these hollow arms 21 serves to deflect the heat arising from the interior of the heater device outwardly and upwardly around the sides of the tea kettle, so that the relatively cool air may readily flow in through the open ends of these hollow arms 21.

I claim as my invention:

1. A heater device comprising in combination a combustion chamber, a hollow heater body supported in the upper end of the combustion chamber and being closed at its bottom and sides and open at its top, and a pipe open at its lower end extended downwardly through the open upper end of the heater body to a point adjacent to the bottom of the interior of the hollow body, the upper end of said pipe being extended to a point spaced above the top of the heater body, and a number of outwardly extended hollow arms communicating with the interior of said pipe at the top and open at their outer ends and designed to support a vessel to be heated.
- 10 15 20

terior of said pipe at the top and open at their outer ends at points spaced laterally beyond the open upper end of the hollow body.

2. A device of the class described comprising a hollow heater body closed at its bottom and sides and open at its top, and a pipe open at both ends and extended downwardly through the open upper end of the heater body to a point adjacent to the bottom of the interior of the hollow body, the upper end of said pipe being extended to a point spaced above the top of the heater body, and a number of outwardly extended hollow arms communicating with the interior of said pipe at the top and open at their outer ends and designed to support a vessel to be heated.

Des Moines, Iowa, March 3, 1924.

CLARENCE H. RASMUSSEN.
